(57) **CLAIM**

The ornamental design for a portion of a television set, as shown and described.

DESCRIPTION

FIG. 1 is a front, top and right side perspective view of a portion of a television set, showing our new design;

FIG. 2 is a front elevational view thereof;

FIG. 3 is a top plan view thereof; and,

FIG. 4 is a right side elevational view thereof, the opposite side being a mirror image thereof.

The bottom plan view and rear elevational view form no part of the claimed design and are hereby disclaimed.

The broken lines are for illustrative only and form no part of the claimed design.
